HANGING HOLDER FOR BATH AND TOILET ARTICLES

Ann Faust, 643 E. 83rd St., Chicago, Ill.

Filed Dec. 22, 1961, Ser. No. 68,037

Term of patent 14 years

(Cl. D4—3)

FIGURE 1 is a front perspective view of a hanging holder for bath and toilet articles, showing my new design; and

The rear surface and the top surface in the closed position are substantially planar.

I claim:

The ornamental design for a hanging holder for bath and toilet articles, substantially as shown and described.
